UNITED STATES PATENT OFFICE.

EDWARD W. COMFORT, OF MERCHANTVILLE, NEW JERSEY, ASSIGNOR TO WARREN WEBSTER & COMPANY, A CORPORATION OF NEW JERSEY.

WATER AND AIR VALVE FOR STEAM-HEATING SYSTEMS.

No. 923,333.

Specification of Letters Patent.

Patented June 1, 1909.

Application filed July 25, 1907. Serial No. 385,415.

To all whom it may concern:

Be it known that I, EDWARD W. COMFORT, of Merchantville, county of Camden, and State of New Jersey, have invented an Improvement in Water and Air Valves for Steam-Heating Systems, of which the following is a specification.

More particularly my invention relates to that class of valves in which the valve-piece which controls the outlet is operated by a motor controlled by the accumulation of the water of condensation in the valve-body, and the air is discharged through a constantly open air duct. To secure the greatest efficiency from each radiating unit it is necessary that all of the steam should be condensed before passing into the return, as any escape or waste of uncondensed vapors means a proportional loss of latent heat units at the radiator. In valves of this character difficulty has been experienced in preventing such waste, as uncondensed vapors are liable to pass through the constantly open duct provided for the discharge of air, and more or less steam is blown through the thoroughfare after the water is discharged and just before the valve fully closes. This is particularly true of vacuum systems in which a suction or partial vacuum is maintained in the returns connected with the outlets of the valves.

It is the object of this invention to effectively prevent this waste of uncondensed steam and vapors either through the air duct or by leakage at the valve-piece.

In the drawings: Figure 1 is a vertical sectional view of a valve embodying the invention; Fig. 2 is a similar view illustrating another form; and Fig. 3 is a transverse section on the line A—A of Fig. 1.

a is the valve-body having an inlet b and outlet c and the valve-passageway or thoroughfare, which latter is preferably in a removable threaded seat-piece i screwed into the body.

e is the motor which carries the valve-piece f. This motor consists of a hollow shell carried by a hollow tube g, the end of which constitutes the valve-piece. The shell e is located at the upper end of the tube g so that the lower end of the tube projects down for a substantial distance below the shell and the shell is elevated above the bottom of the valve-body with its bottom preferably in line with or above the inlet b. From this it re-

sults that a deep well or pocket w is formed in the valve-body below the motor.

j is a guide rod which is carried by the cap k and extends in the tube g preferably for a substantial distance below the bottom of the motor e. This guide is preferably provided with a spiral groove m forming a spiral passageway for air and uncondensed vapor between the tube and guide from the thoroughfare d to the upper part of the valve-body above the motor.

n is a depending wall carried by the cap and surrounding the shell with its lower edge preferably extending below the top of the inlet and substantially level with the bottom of the motor e when the same is in lowered position as in Figs. 1 and 3. In the construction shown in Fig. 1 this wall n is composed of a cylinder carried by the cap k, while in the construction shown in Fig. 2 it is an integral depending portion of the cap below the screw threads.

The air and vapor that enter the valve will pass into the annular space between the motor e and the surrounding wall n thence through the open end of the tube g and down through the spiral passageway between the tube and threaded guide j to the outlet d. Air will pass freely and rapidly, but the passage of uncondensed steam and vapors will be greatly retarded in the spiral passageway, which will act as a spiral capillary duct to condense the vapors, so that practically no uncondensed vapors will escape from said duct into the outlet e and thence into the returns. The water of condensation will accumulate in the well w without causing the motor to operate until it rises into the annular space between the wall n and the motor e, at which time the motor will rise and lift the tube g, allowing the water to flow out until its level falls again below the wall n. The well w will thus be kept more or less full of water about the lower end of the tube g and valve-piece f, and this body of water will act effectively to seal the outlet to the escape of vapor or steam at all times.

By having the extended end of the tube g thus submerged in a well of water below the motor and wall n, I am able to effect the closing of the thoroughfare d before the water has all passed out and the blowing of steam or uncondensed vapors through the thoroughfare just before the valve closes is prevented. The extension of the spiral guide

stem *j* into the lower end of the tube *g* beyond the motor *e* makes of the air passage-way a long capillary duct through which the steam and vapors cannot pass without being 5 condensed. It results therefore that practically no uncondensed vapors will escape and that the maximum efficiency of the steam supplied to the radiating unit will be obtained.

10 What I claim is as follows:

1. A valve for the purpose described consisting of a valve-body having an inlet and an outlet, the inlet being located at a substantial distance above the outlet to form a 15 deep well in the lower part of the valve-body, a movable vertical tube having a contracted passageway through it open at both ends and having its lower end resting on the base of the valve-body and opening into the outlet 20 and carrying the valve-piece to control said outlet, and a float carried by the upper portion of said tube with its bottom at or above the inlet, the lower end of the tube extending below the float through said deep well.
- 25 2. A valve for the purpose described consisting of a valve-body having an inlet and an outlet, the inlet being located at a substantial distance above the outlet to form a deep well in the lower part of the valve-body, 30 a movable vertical tube open at both ends having its lower end resting on the base of the valve-body and opening into the outlet and carrying the valve-piece to control said outlet, a float carried by the upper portion of 35 said tube with its bottom at or above the inlet, the lower end of the tube extending below the float through said deep well, and a 40 guide rod carried by the valve-body and extending down into said tube substantially into the lower end thereof beyond the level of the bottom of the float carried by said tube and forming a contracted passageway with the walls of the tube.

3. A valve for the purpose described consisting of a valve-body having an inlet and 45 an outlet, the inlet being located at a substantial distance above the outlet to form a deep well in the lower part of the valve-body, a movable vertical tube open at both ends having its lower end resting on the base of 50 the valve-body and opening into the outlet and carrying the valve-piece to control said outlet, a float carried by the upper portion of said tube with its bottom at or above the inlet, the lower end of the tube extending 55 below the float through said deep well, and a spirally grooved guide rod carried by the valve-body and extending down into said tube substantially into the lower end thereof beyond the level of the bottom of the float 60 carried by said tube and forming a contracted spiral passage way with the walls of the tube.

4. A valve for the purpose described consisting of a valve-body having an inlet and 65 an outlet, the inlet being located at a substantial distance above the outlet to form a deep well in the lower part of the valve-body, a movable vertical tube open at both ends having its lower end resting on the base of 70 the valve-body and opening into the outlet and carrying the valve-piece to control said outlet, a float carried by the upper portion of said tube with its bottom at or above the inlet, the lower end of the tube extending 75 below the float through said deep well and said tube having a contracted passageway through it, and a wall surrounding said float and having its lower edge substantially level with the bottom of said float.

In testimony of which invention, I have hereunto set my hand.

EDWARD W. COMFORT.
